UNITED STATES PATENT OFFICE

JOSEPH A. FERLAND, OF NORWOOD, MASSACHUSETTS

SNOW REMOVER

Application filed March 5, 1928. Serial No. 259,351.

This invention relates to an apparatus for removing snow, dirt, or other débris from streets, and the object of the invention is to provide a tractor having a forward extension carrying a snow-removing device into which the snow can be readily loaded as the tractor moves forward, and from which the snow can be easily discharged.

One of the objects of the invention is to provide a device of this character with a body to receive the snow which can be tilted about an axis located adjacent its forward end so that the bottom thereof may be normally supported in substantially horizontal position during the loading of the snow and tilted to inclined position for the purpose of discharging the snow.

A further object of the invention is to provide a travelling endless carrier alternatively operable to move the snow rearwardly and forwardly when the body is in horizontal or inclined position.

Another object of the invention is to provide an extensible shovel slidably mounted upon the extension of the tractor frame with means for moving the same into operative position relatively to the front end of the body, or to inoperative position beneath the body.

A further object of the invention is to provide mechanisms operable by the power of the tractor and in convenient control of the operator, respectively, (1) for moving the shovel to and from operative position; (2) for tilting the body; and (3) for controlling the direction of movement of the travelling endless carrier.

These and other objects and features of the invention will more fully appear from the following description and the accompanying drawings and will be particularly pointed out in the claims.

In the drawings:

Fig. 1 is a side view, partially in vertical longitudinal section, of an apparatus embodying the invention;

Fig. 2 is an enlarged plan view of the snow removing part of the same;

Fig. 3 is a detail front elevation of the

mechanisms, illustration of the tractor being omitted;

Fig. 4 is a detail plan view illustrating the relation of the mechanisms for raising and lowering the body and for extending and retracting the shovel;

Fig. 5 is a detail view illustrating the mechanism for tilting the body;

Fig. 6 is a plan view of a portion of the mechanism illustrated in Fig. 5;

Fig. 7 is an enlarged detail view, partially broken away to illustrate the mechanism employed in moving the shovel to and from operative position;

Fig. 8 is an enlarged detail view of the mechanism for actuating and controlling the endless conveyer;

Fig. 9 is a view illustrating the mechanisms by which the operator controls the direction of movement of the endless carrier, and which is also illustrative of similar operating mechanism for controlling other mechanisms from within the cab of the tractor; and,

Fig. 10 is an enlarged view, mainly in vertical section, and similar to a portion of Fig. 1, illustrating the shovel in retracted position, and showing it in operative position in dotted lines.

A preferred embodiment of the invention illustrated in the accompanying drawings comprises a tractor having its frame extended forwardly with the body of the snow removing device pivotally mounted upon the front end of such extension, with means for tilting the body from and toward substantially horizontal position, an extensible shovel slidably mounted upon the frame extension with means operable when extended beyond the end of the tractor frame to position the shovel in operative relation to the body, and an endless conveyer having its upper lead engaging or lying in proximity to the bottom of the body with means, under the control of the operator, for actuating said endless conveyer in such a manner as to carry the snow rearwardly in the body during the loading operation when the bottom of the body is substantially horizontal, or toward the open front end of the body to discharge the load, the latter opera-

60

tion taking place preferably when the body is in tilted position.

As illustrated in the drawings the tractor 10 is provided with a cab 11, containing the driver's seat, located at the rear of the vehicle. The purpose of this arrangement is to enable the front of the vehicle to be provided with an extension for supporting the snow removing apparatus. All of the controlling mechanisms are actuated through rods 13 which extend into the cab in convenient reach of the operator. The frame of the tractor is provided with an extension which supports the body 12 and all of the mechanisms comprising the snow removing apparatus.

The body 12 comprises a bottom, two sides and a closed rear end, the front being open. This body is pivotally mounted at its front end upon a shaft 16 which is journalled in suitable bearings on the front end of the forward extension of the frame of the chassis, and is driven by suitable worm gear mechanism including worm gears mounted upon the ends of the shaft. The shaft has fixedly secured to it near its ends sprocket wheels 18 and similar sprocket wheels 18 are secured to a shaft 17 which is mounted in bearings extending downwardly from the bottom of the body in proximity to its rear end. An endless conveyer having lags 20 passes over these sprocket wheels with the upper lead of the conveyer engaging or in proximity to the upper face of the bottom 14 of the body with the lower lead of the conveyer below the bottom.

Means are provided which are alternatively operable to drive the conveyer in opposite directions so that when driven in one direction the snow will be carried from the front end of the scoop to the rear in the loading operation, and when driven in the other direction will move the snow from the rear toward the front to aid the unloading thereof.

The conveyer is actuated by a shaft 21 which is driven by suitable mechanisms (not shown) from the motor of the vehicle. The front end of the shaft 21 (see Fig. 8) is provided with a beveled gear 22 which is adapted to be selectively engaged by reversely disposed beveled gears 23 and 24 which are slidably feathered upon a shaft 27 and are controlled by a yoke-shaped lever 25 having connected to it a link 26 which in turn is connected to the lower end of a lever 26' (see Fig. 9), the upper end of which lever is connected to one of the controlling links 13 which extend into the cab. The shaft 27 is provided at its ends with gears 28 and 29 which engage complementary gears upon shafts 30 having at their opposite ends worms which engage the worm wheels 15.

By reason of this construction it will be obvious that when the operator actuates the

control rod 26, to cause engagement between the gear 23 and the gear 22, the endless belt may be moved in a direction to cause the lags thereof to move toward the rear of the body to aid in the loading operation, whereas if the controlling mechanism is so operated as to cause the gear 24 to engage the gear 22 the direction of movement of the endless carrier will be reversed and will aid in the unloading of the snow. If the controlling mechanism is so actuated as to remove both gears 23 and 24 from engagement with the gear 22, the endless conveyer will remain at rest.

During loading, the body should remain in horizontal position while removal of the snow from the body will be facilitated if the rear end of the body is tilted upwardly. The mechanism for accomplishing this purpose comprises curved racks 31 (see Figs. 1 and 5) which are fixedly secured upon the outside of the rear end of the body and a shaft 42, which is mounted upon forward extensions from a vertical standard extending upwardly from the frame, and is provided with gears 43 which engage the racks 31. The shaft 21 has slidably feathered to it two gears 33 and 34 adapted selectively to mesh with a gear 35 upon a vertical shaft 36, the upper end of which is rotatably mounted in a bearing upon a boss extending forwardly from the vertical standard and is provided with a worm 37 which engages a worm gear upon a transverse shaft 38, the opposite ends of which are provided with sprocket wheels 39. A sprocket chain 40 is actuated by each sprocket gear 39 to rotate a sprocket wheel which is fixedly secured to the shaft 42 and thereby to rotate the gears 43 which engage the rack 31.

The mechanism for shifting the gears 33 and 34 into or out of engagement with the gear 35 comprises a fork or yoke-shaped lever similar to the lever 25 above described and which is provided with an arm to which one of the controlling rods 13 is connected, as illustrated in Fig. 5.

It will be obvious that when the gear 33 is placed in mesh with the gear 35, as illustrated in Fig. 5, rotation of the shaft 21 will rotate the shaft 36 in a direction to cause the rotation of the gear 43 to raise the rear end of the body 12 and thereby tilt it to discharging position, whereas engagement of the gear 34 with the gear 35 will cause the gear 43 to rotate in the opposite direction and thereby lower the body to horizontal position.

One of the principal objects of the invention is to provide an extensible shovel which, when in operative position, will deliver the snow into the front end of the body 12 as the tractor moves forward, but which can be withdrawn from operative position beneath the body when the snow is to be unloaded from the body.

As illustrated in the accompanying drawings the shovel comprises a front section in the form of a flat plate 50 which desirably is provided with a serrated or toothed front edge 53 to engage the ground. The plate 50 is pivotally connected at its rear end to the front end of a flat plate 54 and the opposite end of the plate 54 is pivotally mounted upon blocks 55 which are slidably mounted in ways 10 upon the forward extension of the chassis frame.

The blocks 55 are moved in their ways by long screws 56 which are actuated by mechanisms hereinafter to be described to move the 15 shovel into operative position beyond the end of the body, or into inoperative position beneath the bottom of the body. A spiral spring 57, which is connected at its respective ends to the plates 50 and 54, provides 20 means for causing the plates to buckle about their hinged connection into a position in which the plate 50 is adapted to direct the snow into the body, but permits the plates to be extended into substantially the same plane 25 when the shovel is to be retracted beneath the body.

The mechanism for extending the shovel into operative position or for withdrawing it into inoperative position beneath the body 30 comprises a beveled gear 60 upon the shaft 21, (see Fig. 7), which is adapted to be selectively engaged by gears 61 and 62 which are slidably feathered upon shafts 63 and 64 and are controlled by a yoke-shaped lever 65 having 35 an arm which is pivotally connected to a link 66 which in turn is connected to one of the controlling rods 13 in any suitable manner as through lever mechanisms such as is illustrated in Fig. 9.

40 The shafts 63 and 64 are provided at their outer ends with beveled gears 67 and 68 which mesh respectively with complementary beveled gears 69 and 70 upon the screw threaded rods 71 and 72 which engage the blocks 55. A sprocket chain 73, which engages suitable sprocket wheels upon the rods 71 and 72, serves to rotate them in unison whether driven by the gears 62 or 63.

By virtue of this construction it will be 50 obvious that when the gear 60 is in engagement with the gear 61, as illustrated, the rods 71 and 72 will be rotated in a direction to move the blocks 55 toward the front end of the vehicle, thereby moving the shovel beyond 55 the end of the body. As the shovel is thus moved forwardly the spring 57 acts to buckle the two sections 50 and 54 upwardly so that the rear edge of the section 50 will extend in close proximity to the front end of the body, 60 while the section 54 of the shovel will be in a substantially vertical position and may engage the end of the body. When in this position and the tractor moving forwardly the snow will be forced upwardly along the section 65 50 of the shovel into the body. The end-

less conveyer may then be operated in a direction to carry the snow rearwardly toward the rear end of the body, thereby enabling the body to be properly loaded.

When the loading operation is completed 70 the lever 65 may be actuated to bring the gears 62 into mesh with the gear 60 thereby rotating the screw threaded rods 71 and 72 in the opposite direction, thus withdrawing the blocks 55 rearwardly and causing the section 54 of the shovel to enter the guideways. Upon continued movement the sections of the shovel will be brought toward alinement, this being permitted by the stretching of the spring 57. The retraction of the shovel may 80 be continued until it is withdrawn into the position illustrated in Fig. 10.

While the load is being transported by the tractor all of the selectively operable gears will remain in neutral position. When the 85 destination is reached and the load is to be discharged, the gear 33 is placed in mesh with the gear 43 to cause the rotation of the gear 43 to raise the rear end of the body and tilt the body into discharging position. The lever 90 controlling the gears for actuating the endless conveyer may then be actuated to cause the gear 24 to engage the gear 22 and actuate the endless carrier in a direction to aid in unloading the snow.

Having thus described the invention, what 95 is claimed as new, and desired to be secured by Letters Patent, is:

1. An apparatus of the class described comprising a tractor, a body to receive the snow mounted upon the front end thereof, an extensible shovel formed in sections pivotally connected together, means for supporting the shovel beneath the body, means for moving the shovel beyond the front end of the body, and resilient means operable to position the shovel sections in angular relation with the front section of the shovel inclined to deliver snow into the open end of the body.

2. An apparatus of the class described comprising a tractor having a forwardly extending frame, a body to receive the snow pivotally mounted at its front end upon said frame, an extensible shovel slidably mounted beneath said body, means for moving the shovel into operative position beyond the end of said body, and means for pivotally moving said body from substantially horizontal position to an inclined position to aid in removing the load.

3. An apparatus of the class described comprising a tractor having a forwardly extending frame, a body to receive the snow pivotally mounted at its front end upon said frame, an extensible shovel slidably mounted beneath said body, means for moving the shovel into operative position beyond the end of said body, means for pivotally moving said body from substantially horizontal position to an inclined position to aid in remov-

ing the load, and means within said body selectively operable to move the snow toward the rear of the body during the loading thereof, or toward the front of the body during unloading.

5. An apparatus of the class described comprising a tractor having a forward extension, a body having an open front end to receive the snow mounted upon said extension, a shovel formed in sections slidably mounted beneath said body and means actuated by power from said tractor, selectively operable under the control of the operator, to move said shovel into operative position with respect to the open front end of said body, or to withdraw it into inoperative position beneath said body.

5. An apparatus of the class described comprising a tractor having a forward extension, a body having an open front end to receive the snow pivotally mounted at its front end upon said extension, a shovel formed in sections slidably mounted beneath said body, and means actuated by power from said tractor, selectively operable, under the control of the operator, to move said shovel into operative position with respect to the open end of the body, or to withdraw it into inoperative position beneath said body, and means actuated by the power from said tractor selectively operable, under the control of the operator, to tilt said body from substantially horizontal loading position to inclined load-discharging position.

35. An apparatus of the class described comprising a tractor having a forward extension, a body having an open front end to receive the snow mounted upon said extension, a shovel formed in sections slidably mounted beneath said body and means actuated by power from said tractor, selectively operable, under the control of the operator, to move said shovel into operative position with respect to the open front end of said body, or to withdraw it into inoperative position beneath said body, an endless conveyer mounted on the bottom of said body, and means actuated by power from said motor selectively operable, under the control of the operator, to cause said endless conveyer to move in a direction to carry the snow toward the rear of said body during loading and to force said snow toward the open end of said body during unloading.

55. An apparatus of the class described comprising a tractor having a forward extension, a body having an open front end to receive the snow pivotally mounted at its front end upon said extension, a shovel formed in sections slidably mounted beneath said body, and means actuated by power from said tractor, selectively operable, under the control of the operator, to move said shovel into operative position with respect to the open end of the body, or to withdraw it into

inoperative position beneath said body, and means actuated by the power from said tractor selectively operable, under the control of the operator, to tilt said body from substantially horizontal loading position to inclined load-discharging position, an endless conveyer mounted on the bottom of said body, and means actuated by power from said tractor selectively operable, under the control of the operator, to cause said endless conveyer to move in a direction to carry the snow toward the rear end of said body when loading or to force said snow toward the open front end of said body during unloading.
